His attorney.

UNITED STATES PATENT OFFICE.

CHRISTIAN STEENSTRUP, OF SCHENECTADY, NEW YORK, ASSIGNOR TO GENERAL ELECTRIC COMPANY, A CORPORATION OF NEW YORK.

ELECTRICAL HEATING ELEMENT.

Application filed March 30, 1923. Serial No. 628,927.

To all whom it may concern:

Be it known that I, CHRISTIAN STEENSTRUP, a citizen of the United States, residing at Schenectady, in the county of Schenectady, State of New York, have invented certain new and useful Improvements in Electrical Heating Elements, of which the following is a specification.

The present invention relates to electrical heating elements or units such for example, as are commonly used for household and other purposes and has for its object to improve their construction.

In the manufacture of these elements or units it is common practice to use what is known as "sheathed wire" for the heating element. Briefly, this comprises a wire made of high resistance metal through which the heating current flows. Enclosing the wire is a steel sheath or armour and between the wire and the sheath is a closely compacted insulating material such as magnesia. After being properly formed the sheathed wire may be coiled, bent or otherwise formed into a heating unit having the necessary electrical characteristics.

Heating units made in this manner have been incorporated in the finished article in a variety of ways, one of which is by casting. That is to say, the complete heating element is suitably placed in a mold after which molten metal, such as iron or aluminum is poured into the mold to fill the same. The metal when cooled forms a completed enclosure for the unit except for the terminals which project through the body for connection with the circuit wires.

In the casting operation there are many rejections due to imperfections as for example, blow holes and failure of the molten metal to completely fill the mold, all of which results in a considerable loss both in money and material. There is no fusion between the embedded article and the casting but instead merely surface contact and the heat conductivity is impaired for that reason. It also frequently happens that even this contact is not maintained and as a result one or more small chambers or pockets are formed alongside of the sheath and between it and the surrounding metal. Such a pocket is a potential danger spot because the transfer of heat from the unit to the surrounding metal at this point is impaired

with the result that the heating unit burns out or short circuits at said point. This is a very serious matter because it is impossible to detect these pockets in the finished product by usual testing methods and hence there is no way to ascertain that the product is defective until after it is put into use.

In carrying out my invention, the sheathed wire is formed into a heating unit of any desired shape or form. It may be used in straight lengths, coiled, bent or otherwise arranged, the only limitation being that the core wire be properly insulated from the sheath and have the necessary resistance to the flow of current and supply the necessary amount of heat for the purpose intended. Assuming the unit to be properly formed, it is placed in a suitable container which may be made of metal or heat resisting material or a combination of both. When made of suitable metal, such as steel, the container in addition to acting as a receptacle for the heating unit also forms an integral part of the finished device. The mold is then filled with a composite metal invented by me and which forms the subject matter of another application filed of even date herewith Serial No. 628,926. Briefly stated, it comprises a base material comprising smooth-surfaced, self-packing particles of metal, the voids between said particles being of a capillary nature. Such particles when poured into a container freely distribute themselves or pack in much the same way that lead shot will fill a container when poured into it. By avoiding the use of pressure on the particles all danger of distorting the heating unit or parts thereof is avoided. For the purpose of the present invention it is preferable to use small shot made of mild steel having a low carbon content. The diameter of the shot can be varied between rather wide limits. The main considerations are that the material be self-packing and that the voids between the particles or shot be of a capillary nature. To the base metal is added a void-filling and fusing metal of lower melting point and in sufficient amount to fill the voids thereof. This metal is preferably supplied in the form of small pieces distributed over the top of the shot. Where the shot are made of steel, copper is used as the void-filling and fusing metal. To obtain the best results

boronized copper should be used or copper that has been treated in a hydrogen furnace, to remove the impurities. At this stage in the process all the parts are or may be at 5 room temperature.

The self-packing feature of the material and the character of the voids is of the utmost importance for this class of work. If the particles are rough they will not be self 10 packing and the size of the voids will vary unduly. While the shot may be very small, they are nevertheless of appreciable size, and as bearing on this point, if the particles are reduced to powder form they will not be satisfactory 15 because the fusing metal will not penetrate the mass and in flowing will pick up the powder which changes its melting point. I have also found that the resulting product shrinks to a substantial degree and 20 also cracks and is not dense and homogeneous.

Having assembled the heating unit within the container and filled the latter with steel shot, the next step is to place the container and its contents in a closed furnace in which an atmosphere of selected gas is constantly maintained. When steel and copper are used to form the composite enclosing metal for the unit, hydrogen gas is best 25 adapted for the purpose. The contents of the container are then heated to a temperature sufficiently high to melt the copper, which temperature will not injure the heating unit nor melt the shot. To obtain the 30 best results the copper should be distributed rather uniformly over the shot. As already pointed out this may be done by distributing or sprinkling small pieces of copper over the exposed upper surface of the body of 35 shot or it may be supplied in fluid form from a coarse mesh screen or equivalent device suitably placed above the container and from which the molten copper is free to flow onto the shot. My experience has demonstrated 40 that if sufficient molten copper is permitted to accumulate at any point in the container, so as to form a pool, it causes a disturbance of the steel shot with the result of impairing the homogeneity of the 45 finished product. When the necessary temperature is reached the copper will flow by capillary action into the voids between the shot and fill them. This heating action causes fusion of the parts and also a certain 50 alloyage of the copper with the sheath of the wire, with the steel shot and also with the inner walls of the container if it be made of suitable metal. The composite metal thus 55 formed does not shrink and crack in cooling and is therefore well adapted for the purpose. 60

Owing to the small size of the shot employed they fill all the spaces between the turns or parts of the heating unit and the 65 container and the voids are filled with cop-

per. Due to this fact and to the complete fusion of the parts a very intimate thermal connection is obtained between the wall or sheath of the heating unit and the surrounding metal and the impaired heat transmission and pockets which are so highly objectionable in the casting process above referred to are entirely avoided. 70

The composite material has about the same strength as that of mild steel and can 75 be treated in the same way. That is to say, it can be rolled, drawn, swaged, forged and machined. This means that the surfaces of the completed product can be finished with ordinary machine tools. 80

In the accompanying drawing, which is illustrative of my invention, Fig. 1 is a plan view of a sheathed wire heating unit located in a container, Fig. 2 is a sectional view of the same; Fig. 3 shows a container made of heat-resisting material; Fig. 4 is a plan view of a container and heating unit suitable for a flat iron; Fig. 5 shows another way for making a container; Fig. 6 shows on a greatly exaggerated scale the steel shot used as the base of the composite material, and Fig. 7 is a view of a piece of resistance material, such as wire, covered with insulation capable of withstanding high temperatures, the sheath being omitted. 95

10 indicates a container which can be pressed or stamped out of sheet steel to the exact size and shape required. In general it is shallow, so that the finished product will be thin, thus avoiding the necessity of heating any substantial amount of metal. The sheathed wire heating unit 11 which may be of any suitable size and shape is placed in the bottom of the container or it may be spaced therefrom by first pouring 100 in some of the steel shot and leveling them off to the desired thickness as in Fig. 3 for example. After the unit is placed in position steel shot are poured into the container to the level of the top. The container may be jarred slightly to facilitate the settling of the shot. The ends 12 of the heating unit may be bent upwardly so as to afford means for connecting the unit to the circuit wires of the source of supply. 13 indicates the resistance wire and 14 the steel sheath therefore, there being insulation between the two. Copper in small pieces is then distributed over the steel shot and then the container and its contents are treated 115 in a closed furnace in a hydrogen atmosphere as above described. 120

Fig. 3 shows a different form of container. In this case it is composed of a body of heat-resisting material 16 which is composed of hard-pressed asbestos or asbestos compound. In this case a layer of steel shot is placed in the container before the unit is inserted so as to provide a surface which later on can be machined. The container is 125 130

then filled to the level of the top with steel shot over which the necessary amount of copper is distributed, after which the container is placed in a closed furnace as before. This type of container may be made in one or more pieces.

Fig. 4 shows my invention applied to a flat-iron. In this case a shallow sheet metal container 17 is pressed up to the desired shape and size, after which the sheathed wire heating unit 18 is inserted. It may rest directly on the bottom of the container or be spaced therefrom in the manner previously described. Subsequent operations are the same as those above recited. The shoe thus formed may be used with any desired form of holder.

In Fig. 5 is shown a container composed partly of metal in the form of vertical walls 19 and a base of heat-resisting material 20.

Fig. 6 shows on a greatly exaggerated scale the steel shot 21 employed in the process, said shot being as above stated of such size in actual practice that the voids between them are of a capillary nature.

In addition to the advantages specifically set forth above, the resulting product may be made very thin, and in any case the enclosing metal will be dense and homogeneous throughout. In the making of pots, kettles, etc., the heating unit may be located directly in the bottom and fused to it and the side walls by the methods herein described.

Where a pressed metal container is employed for the heating unit it is unnecessary for most purposes to finish the outer surface thereof unless a special finish is desired, as for example one of nickel plate. The finish resulting from the type of molds shown in Figs. 3 and 5 is good enough for many purposes, and where it is not, a simple machine operation will suffice.

In another, and in some respects, a simpler form of my invention the steel sheath is omitted altogether and the resistance material 13 Fig. 7 is coated with an insulating material 22 which of itself is capable of withstanding the necessary high temperature to melt the copper without disintegration or injury. In such a case the resistance material may be coiled, bent or otherwise formed to shape and afterwards coated with insulation, or the insulation may be applied before the forming operation whichever is the most convenient. After the heating unit is thus formed it is placed in a container and the surrounding portions of the chamber filled with steel shot as before, so as to embed the unit therein. The subsequent operations are the same as those already described. The transfer of heat from the unit to the holder or supporting material is about the same in both cases because substantially the same amount of in-

sulation has to be used in any event to electrically insulate the resistance material from its metallic holder or support.

What I claim as new and desire to secure by Letters Patent of the United States, is:

1. The combination of an electrical heating unit composed of resistance material, insulation therefor, and a holder in which the unit is embedded, comprising a base of self-packing metal particles and a metal having a lower melting point than the said particles which fills the voids and unites them into a unitary mass, which mass has greater strength than said metal of lower melting point.

2. The combination of an electrical heating unit composed of resistance material, an insulating envelope therefor, and a holder in which the unit is embedded comprising a base of steel shot and another metal having a lower melting point than the shot which fills the voids between the shot and unites them, said holder having a strength substantially the same as the shot.

3. The combination of an electrical heating unit composed of resistance material, an insulating envelope therefor, a container in which the unit is located, and a filler for the container in which the unit is embedded comprising a base of steel shot and copper said copper uniting the shot and the wall of the container and filling the voids between them.

4. The combination of a resistance material which is enclosed in a metallic sheath to form a heating element and from which it is insulated with a holder therefor of composite metal comprising a base of self-packing metal particles and another metal having a lower melting point than the base material which fills the voids in the base material and unites said particles with the sheath.

5. The combination of resistance material which is enclosed in a metallic sheath to form a heating element and from which it is electrically insulated with a holder in which the element is embedded comprising a base of self packing metal particles having voids between them of a capillary nature, and another metal having a lower melting point than the sheath and the particles said other metal filling the voids and intimately uniting the said particles to the sheath.

6. The combination of resistance material which is enclosed in a metallic sheath to form a heating unit and from which it is insulated with a holder therefor of composite metal comprising small metallic shot and a metal which has a lower melting point than the shot, fills the voids between them and the sheath and unites the shot and sheath into a unitary structure, said composite metal having greater strength than the metal of lower melting point.

7. The combination of a heating element

which is enclosed in a metallic sheath with a holder of composite material in which the element is embedded comprising a base material composed of small steel shot, and copper per which fills the voids between the parts and unites them, said composite material being stronger than the copper.

8. The combination of an insulated heating element, a metallic container in which the element is located, and a filling for the container and in which the element is embedded comprising a base material of small self-packing metal particles and another metal of lower melting point which fills the voids in the base material and unites said particles with the container.

9. An electrical heating element which is enclosed in a metallic sheath, a metallic container in which the element is located in spaced relation to the walls thereof, a filling for the container comprising a base of small self-packing metallic particles having voids of a capillary nature, and another metal having a lower melting point which fills the voids between said particles and unites them with the sheath and the walls of the container.

10. An electrical heating element which is

enclosed in a metallic sheath, a shallow steel container in which the element is located in spaced relation to the walls thereof, a filling for the container comprising a base of steel shot having voids of a capillary nature, and copper which fills the voids between the shot and unites them with the sheath and the walls of the container.

11. As an article of manufacture, a steel-sheathed electrical heating element which is embedded in composite metal comprising small steel balls and copper which copper unites the steel balls with the steel sheath, said composite metal having greater strength than copper.

12. An electrical heating element which is enclosed in a metallic sheath and insulated therefrom, a composite metal holder for the element which comprises self-packing metal particles which are in contact with each other and with the sheath and a metal which has a lower melting point than the sheath and particles, fills the voids between them and is slightly alloyed with the surface portions of said parts.

In witness whereof, I have hereunto set my hand this 29th day of March, 1923.

CHRISTIAN STEENSTRUP.
